ROTARY PRINTING APPARATUS

Harmon P. Elliott, Watertown, Mass., assignor to
The Elliott Addressing Machine Company, a
corporation of Massachusetts

Application June 16, 1933, Serial No. 676,033

18 Claims. (Cl. 101—118)

The present invention relates to certain improvements on the general type of machines shown and described in my Patent No. 1,909,910, dated May 16, 1933, for "Addressing and printing apparatus", designed to ensure noiseless operation and certainty of the discharge from the printing zone of the postcards or other articles printed therein.

In the said patent certain rotary friction wheels 36, 36, are shown on which the printed articles rest as they leave the printing zone, and by the action of which the continued movement of said articles into any proper receptacle is ensured, and preferably accelerated, but in said patent such friction wheels are shown as being continuously geared to the printing mechanism. To produce a satisfactory discharge action such friction wheels had to be geared to run at a higher rate of circumferential speed than that at which the printing members rotated, and this involved the expenditure of considerable power, which had to be exerted continuously, whereas it was only needed during a fraction of each cycle of operation, i. e. for a short time after each printing operation had been completed, or nearly completed. Also the construction of such gearing added to the original cost. In the present invention a simple, practically frictionless driving connection between the printing mechanism and such friction wheels has been substituted for the chain and sprockets shown in the patent, and one which comes into operation only during the short period of time when such discharge action is required.

Other features of the present invention relate more particularly to the message printing operations of the machine, in which a large flexible stencil held in a metal carrier is rapidly reciprocated back and forth in the printing zone. The mechanism employed in said patented apparatus for this purpose proved rather noisy as a result of the shuttle-like movement of the carrier, and I have now devised certain modified forms of mechanism for causing its reciprocation which are more nearly noiseless in operation.

The best forms of apparatus at present known to me embodying these several improvements are illustrated in the accompanying two sheets of drawings, in which

Fig. 1 is a side elevation of the delivery end of a printing apparatus such as shown in my above noted patent with one embodiment of the present invention applied thereto.

Fig. 2 is a plan view of the same with parts broken away.

Fig. 3 is a detailed side elevation of a portion of the controlling device for the reciprocating parts, on an enlarged scale.

Fig. 4 is a detail section on line 4—4 of Fig. 1, on an enlarged scale.

Fig. 5 is a plan view, with parts broken away and others shown in section, of a modified form of the controlling device for the reciprocating mechanism, and

Fig. 6 is a side elevation of the same.

Fig. 7 is a cross section on line 7—7 of Fig. 5, on an enlarged scale.

Throughout the drawings like reference characters indicate like parts.

Referring to Figs. 1, 2 and 3, the parts of the printing apparatus therein shown, which are the same as or similar to corresponding parts shown in my above noted patent, comprise a main frame 51 supported by legs, one of which is shown at 52, the extension 76 to said frame supporting guides for stencils, one of which is shown at 9, and a revoluble sector 3 adapted to carry ink on its surface, and connected by gearing 6 to the lower revoluble platen 5. Sector 3 is mounted on shaft 2 which can be rotated by the hand crank 1, and platen 5 is mounted on the shaft 55, both said shafts being journaled in the main frame 51 or in the housing 67 carried thereby. The apparatus above described is shown as arranged to print a message or other printed matter or design on each of a series of postcards 21 by cooperation with the large flexible stencil 7 held in the carrier 8 which slides in grooves in the guides 9 and 99 (the second guide 99 being shown in Fig. 5). The postcards 21 are fed by any desired means along any suitable guides, one of which is shown at 22, Fig. 1, to the printing zone, and during and after the printing operations are discharged by the revoluble printing means 3 and 5 onto the rotating friction discharge wheels or ejector members 36, 36, which are fast on the revoluble shaft 61 journaled in the main frame.

In my above noted patent said discharge wheels 36 are continuously rotated by a chain and sprocket gearing from the shaft 55, and in order to insure the rapid discharge of each card 21 into the receptacle (not shown) provided for it, said gearing is so proportioned as to rotate shaft 61 at a rate of speed sufficient to produce a circumferential speed of the wheels 36 in excess of the circumferential speed of the platen 5, and this of course consumes considerable power.

er which is being expended continuously, between the discharge operations on successive cards as well as during each such operation. Even with the high speed gearing there shown, 5 however, the necessary speed of ejection of the card 21 is not always obtained, and one object of the present invention is to overcome this difficulty and also to reduce the amount of power consumed, as well as to simplify and cheapen 10 the construction.

For obtaining the above outlined objects I substitute for the continuous gearing from the said platen an intermittently acting propulsion mechanism for the ejector means 36, 36, the preferred form of which comprises a circumferential band or tire 63 for the rotor member 62 mounted on the shaft 61 offset laterally from the ejector means 36 and outside of the path of the cards or envelopes 21, and give said rotor a brief but vigorous impulse of rotation by 15 means of a finger 31 projecting radially from the sector shaft 2, and preferably having a sharpened end which is spaced away from the axis of shaft 2 sufficiently to cause it to engage the soft elastic material 63 on rotor 62 during 20 a brief portion only of each cycle of printing operations, thereby giving the rotor a vigorous kick which will spin it long enough to eject the particular card 21 then resting on it. As the finger 31 is considerably longer than the radius 25 of the curved surface of sector 3, its speed of movement is considerably in excess of that of said sector surface, and accordingly the rotor 62 (and the ejector wheels 36 of substantially 30 the same diameter) will be given a circumferential speed considerably in excess of the rate 35 of movement of the postcard coming from the printing zone. Consequently each such card will 40 be discharged rapidly, and before the succeeding card is grasped by the rotating printing means and its printing and discharge movements thereby begun.

This rapidity of motion transmitted to rotor 62 is further increased by hinging the finger 31 45 on pivot 32 offset radially from the shaft 2, and then employing the coil spring 33, one end of which is anchored on the finger while the other is anchored on the crank lug 30 carried by shaft 2. A stop 34 is carried by crank lug 30 and 50 preferably is made of slightly yielding material to avoid noise, and provides a motion limiting engagement when and while finger 31 is forced against it and held in such engagement by action of spring 33. In designing this mechanism 55 the finger 31 should be made of a length such that its tip is spaced away from the axis of shaft 2, when the parts are in the normal position shown in Fig. 1, by a distance somewhat 60 in excess of that from the axis of such shaft to the surface of the rotor 62 along a straight line joining the axes of said shaft and rotor. This causes a slight bending of the knee joint, 65 formed by finger 31 and lug 30 pivoted together at 32, during the first portion of the engagement of the finger with rotor 62 and then, after the pivot 32 has passed far enough beyond the 70 straight line joining the axes of shafts 2 and 61 to permit this knee joint to begin straightening out, the spring 33 gives a quick snap action of finger 31 back against the stop 34, which produces a considerably further acceleration of the 75 impulse of rotation being given to the rotor 62, thereby producing an increased rapidity of ejector action on the card 21 then resting on the wheels 36, 36.

The stencil carrier 8 in all forms of apparatus of the type shown in my above noted patent is constantly reciprocated during the message printing operation part way through the printing zone between the revoluble printing means and then back again to the initial position shown in Fig. 2. As the return of the stencil carrier to this position when released by reason of the rotating sector 3 letting go of it at the close of the printing operation must be very rapid 10 if a single spring is employed for producing it as shown in my said patent, said spring must be of considerable strength, with the result that the metallic carrier 8 comes back against the fixed stop necessarily provided for it with a considerable shock which produces an objectionable noise rapidly repeated during all the shuttle-like action of the message stencil, and the second feature of the present invention embodies modified mechanism for avoiding this continuously 15 increasing rapidity of the return motion of the carrier as it travels backward under the continuous urge of a single sufficiently strong spring and the shock and noise produced by its abrupt stoppage by contact with the fixed stop 20 when at the maximum of such speed.

In the arrangement shown in Figs. 1, 2 and 3, the above stated result is obtained by dividing the production of the carrier returning force between two springs, one being the original tension spring 10 anchored at 11 and connected at the other end to the retracting finger slide 12, which, as shown in my said patent, reciprocates upon a guide rod 13 anchored on the main frame, and has a laterally projecting finger 14 30 overhanging the edge of the stencil carrier 8 and engaged by the upwardly projecting lug on said carrier, and the other being a compression spring 40 also mounted on said rod 13 and confined by the block 41 slidable on the rod and 40 held in adjustable position thereon by setscrew 44. The result of this arrangement is that said tension spring 10 may be much weaker than when it was required to do the entire work of 45 returning carrier 8, and that consequently while during the last portion of the forward travel of the message stencil, and at the moment of its reversal of motion when released by sector 3, it receives for its return movement the sum of the impulses contributed by the compression of 50 spring 40 and the extreme extension of the tension spring 10, so that it starts on its return trip at a high speed, it soon thereafter is relieved from the direct push of the compression spring 40 and continues only by reason of its 55 own momentum and of the decreasing pull of the weak tension spring 10. As a result its speed during the latter part of its return motion is somewhat reduced (or at least is not accelerated) and the shock with which the finger slide 60 12 strikes the rubber stop 17 (Fig. 3) is greatly reduced.

Also such shock is further reduced by means of the bent spring 43 anchored on the base 101 of the stencil magazine 50, the upwardly inclined outer end of which is struck by the lug 42 on the finger slide 12. Said spring 43 and lug 42 also serve the useful purpose of forming a spring latch after lug 42 has passed under the bent end of spring 43, which positively holds 70 the finger back in extreme righthand position so that the stencil 7 is in correct registry for the repetition of the printing operation. To reduce the shock and noise in the manner previously described by reducing the strength of the spring 75

10 the effective pull of the latter when completely contracted at the expiration of the return movement of the stencil may have been so reduced that unless some such spring latch 5 construction is employed the slide 12 may rebound slightly after striking the rubber stop 17, and so leave the stencil 7 out of registry for the next printing operation. The guide rod 13 is rigidly supported at the lefthand end on guide 10 9 by the lug 35, and at the righthand end it is screwed into the magazine base 101, as best shown in Fig. 3.

The last above described apparatus materially reduces the shock and noise resulting from the 15 shuttle-like action of the stencil carrier, but these may be still further reduced by omitting spring 10 altogether and employing an air-cushion stop of the type illustrated in Figs. 5 to 7, the compressor spring (there marked 98) 20 being made stronger so as to do all the work of returning the stencil to initial position. In this construction, the upwardly projecting lug 15 on the stencil carrier 8 is engaged by the hook 28 on the end of piston rod 95 which extends from 25 piston 94 reciprocating in cylinder 93, which is preferably pivotally mounted on stencil guide 9 by means of the pivot pin 24 projecting from base plate 23 on which cylinder 93 is mounted, said pivot pin being held in engagement with 30 guide 9 by thumbnut 25.

Cylinder 93 has a stuffing box 97 on its right-hand end through which piston rod 95 reciprocates, and 16 is a stop member carried by the piston and cooperating with the buffer disk 88

35 in that end of the cylinder, and also serving to connect piston rod 95 with piston 94. A rearwardly extending piston rod 96 passes through the lefthand, open end of cylinder 93 and through a fixed guide 28. A compression spring 40 98 is mounted on extension piston rod 96 and compressed between guide 28 and piston 94. The piston 94, preferably having a packing leather of the usual lip or U-shaped cross section, permits air to pass around it into the closed end 45 of cylinder 93 when the stencil is pulled to the left by the revoluble printing members 3 and 5, thus pushing said piston also to the left by means of the piston rod 95. When the stencil carrier 8 is released by continued rotation of the 50 sector 3 spring 98 expands and drives the piston and the stencil back to the right, to the latter's initial position, ready for a repetition of the printing operations. During the first portion of this return motion the parts move quite rapidly 55 because of the extreme degree of compression of spring 98 and the free expulsion of air in the righthand, closed end of cylinder 93 through a port 87. When however the return movement of the stencil has been nearly accomplished a 60 valve 89, carried by piston 94, closes port 87, and thereafter the air trapped in the closed cylinder end can only escape slowly through the stuffing box 97 or around piston 94, with the result that the return movement of the stencil 65 7 is gradually and noiselessly checked until it comes to final rest when the piston extension or stop 16 reaches the buffer 88.

I have shown the connection between the piston rod 95 and the stencil carrier 8 in the form 70 of the hook 28 engaging the lug 15, and in order to maintain the engagement of the lug by this hook I employ a fixed spring 27 bearing on cylinder 93 and normally tending to swing it in a counterclockwise direction (looking at Fig. 5). 75 As cylinder 93 is pivoted on the guide 9 this

pivotal mounting is somewhat offset from the line of travel of lug 15 and the constantly varying angularity of piston rod 95 will cause the cylinder 93 to oscillate slightly on its pivot 94 during each operation, but the flexibility of spring 27 permits this while maintaining the engagement of hook 28 with the lug 15 as above described. 26, 26, are stop pins mounted on the corners of the swinging bed plate 23 and limiting its motion within predetermined bounds in 10 case hook 28 should jump out of engagement with lug 15.

Other slightly flexible connections between piston rod 95 and stencil carrier 8 might be substituted for the lug 15 and hook 28 loosely engaging said lug above described.

Obviously the ejector device hereinbefore described will discharge the printed cards or envelopes or sheets of paper rapidly and surely, thus getting them out of the path of the next 20 article which is being printed, and so preventing any clogging of this portion of the apparatus on the discharge side of the printing zone, but the total power consumed in such ejecting operation during each printing cycle will be 25 small. Also it will be seen that the various forms of the device here shown for lessening the shock heretofore created in suddenly stopping the reciprocating stencil after it has been snapped back into its position of intermittent, 30 brief rest, will reduce the noise of that operation. Especially is this true of the air cushion form shown in Figs. 5 to 7.

Various changes could, of course, be made in the details of construction here disclosed without departing from the underlying principles of the invention, so long as the same mode of operation is substantially preserved, and the same result obtained in whole or in substantial part.

Having described my invention, I claim:

1. In a printing apparatus comprising oppositely revoluble printing members, one of which carries ink, and between which articles to be printed may be fed, the combination, with said above described apparatus, of a rotary ejector 45 member journaled on the discharge side of said printing members and provided with a rotor located at one side of said ejector member and outside of the path of the articles being printed, together with a finger connected to one of said 50 printing members having a length sufficient to cause it to engage said rotor during a portion of each revolution of said finger; whereby said ejector member is rotated by intermittent impulses.

2. A combination such as defined in claim 1 in which said finger projects beyond the circumferential surface of the printing element to which it is connected and is longer than the radius of rotation of the surface of the rotor member with which said finger engages; whereby a speed of rotation is given said rotor greater than that of said printing member.

3. A combination such as defined in claim 1 in which said rotor is provided with a friction producing surface with which the extremity of said finger engages at a predetermined point in each revolution of the latter.

4. A combination such as defined in claim 1 in which said rotor is provided with a friction producing surface with which the extremity of said finger engages at a predetermined point in each revolution of the latter, said friction producing surface consisting of a circumferential band of yielding material, and said finger ex- 75

tremity being sharpened so as to slightly embed itself in said material during the period of its engagement therewith.

5. A combination such as defined in claim 1 in which the connection between said finger and printing member is hinged and spring controlled.

6. A combination such as defined in claim 1 in which the connection between said finger and printing member is hinged and spring controlled, the axis of said hinge being offset from the axis of said member.

7. In a printing apparatus comprising oppositely revoluble printing members, one of which carries ink, and between which articles to be printed may be fed, the combination, with said above described apparatus, of a rotary ejector member journaled on the discharge side of said printing members and below the path of the printed articles, said ejector member being provided with a rotor offset laterally therefrom far enough to be outside of the path of the printed articles, together with a finger having a hinged connection to the printing member which is located above said path of the printed articles, a stop member rigidly mounted on said printing member, and a spring normally forcing said finger toward said stop member, said finger revolving in the plane of said rotor and being long enough to engage the latter when it is held against said stop by said spring.

8. A combination such as defined in claim 7 in which said rotor has a circumferential surface of yielding material and said finger has a sharpened extremity; whereby said finger extremity may slightly embed itself in said yielding material when forced into contact therewith.

9. In a rotary printing apparatus comprising a pair of revoluble printing members, one of which is cut away along an arc of its surface, means for revolving said members in opposite directions, a stencil, and guides along which said stencil may be reciprocated between said members, a reciprocable device, means for confining the reciprocation of said device to a line substantially parallel to said guides, mechanism for causing said device to move synchronously with said stencil, and a spring for pulling said reciprocable device back along said guides whenever the stencil is released by such printing members after each printing operation, the combination, with said above described apparatus of a compression spring anchored relatively to said guides and located in the path of travel of said device while it is moving with said stencil during a printing operation; whereby said spring is compressed at the completion of such printing operation and on release of the stencil by further rotation of said printing members, expands to drive said reciprocable device and stencil back towards their initial positions in which they are ready for a repetition of such printing operation.

10. An apparatus such as defined in claim 9 in which said reciprocable device completes a portion of its travel before engaging said last mentioned spring, and in which said first mentioned spring is weaker than is said last mentioned spring, and is so connected to said device as to be flexed during all portions of the latter's reciprocation.

11. An apparatus such as defined in claim 9 combined with a spring latch adapted to grasp said reciprocable device when in its position of rest, and yieldingly hold it in said position.

12. An apparatus such as defined in claim 9 in which said reciprocable device is provided with a laterally projecting lug, combined with a stationary yielding member having a surface inclined to the line of reciprocation of said member which is so located as to engage said lug just before said member reaches the end of its return movement.

13. In a rotary printing apparatus comprising a pair of revoluble printing members, one of which is cut away along an arc of its surface, means for revolving said members in opposite directions, a stencil, and guides along which said stencil may be reciprocated between said members, the combination, with said above described apparatus of an air-cushioning mechanism anchored relatively to said guides, and a connection from the movable member of said mechanism to said stencil, together with a spring acting to return said stencil to its initial position after it is released by said printing members, and overcoming the resistance of said air-cushioning mechanism when so acting.

14. A combination such as defined in claim 13 in which said air-cushioning mechanism comprises a cylinder open to the air at one end but closed at the other end with the exception of a small leakage port, and a piston in said cylinder having a piston rod projecting from said cylinder, and in which the connection from such air cushioning mechanism to said stencil comprises a carrier for the latter provided with an upwardly projecting lug, and a hook on the end of said piston rod adapted to engage said lug.

15. A combination such as defined in claim 13 in which said air cushioning mechanism comprises a cylinder open to the air at one end but closed at the other end with the exception of a small leakage port, and a piston in said cylinder having a piston rod projecting from said cylinder, and in which the connection from such air cushioning mechanism to said stencil comprises a carrier for the latter and a flexible linkage between said carrier and piston rod, said cylinder being pivoted on one of said guides.

16. An apparatus such as defined in claim 13 in which said air cushioning mechanism comprises a cylinder pivoted on one of said guides and open to the air at one end but closed at the other end with the exception of a small leakage port, and a piston in said cylinder having a piston rod projecting from said cylinder; and in which the connection from such air cushioning mechanism to said stencil comprises a carrier for the latter provided with an upwardly projecting lug, and a hook on the end of said piston rod adapted to engage said lug, combined with a spring normally tending to swing said hook toward said lug.

17. In a rotary printing apparatus comprising a pair of revoluble printing members, one of which is cut away along an arc of its surface, means for revolving said members in opposite directions, a stencil, and guides along which said stencil may be reciprocated between said members, the combination, with said above described apparatus of a reciprocable device, means for confining the reciprocation of said device to a line substantially parallel to said guides, mechanism for causing said device to move synchronously with said stencil, and a spring latch for yieldingly holding said reciprocable member in the position occupied by it when said stencil is at rest.

18. In a rotary printing apparatus comprising

ing a pair of revoluble printing members, one of which is cut away along an arc of its surface, means for revolving said members in opposite directions, a stencil, and guides along which said 5 stencil may be reciprocated between said members, the combination, with said above described

apparatus of latch mechanism acting to yieldingly hold said stencil in the position occupied by it when at rest and spring means acting to return it to said position whenever released by said printing members.

HARMON P. ELLIOTT.
